Franklin J. Repp and Harry P. Yeager, Milwaukee, and Louis B. Robbin and Louis B. Robbin, Jr., Eagle, Wis.

Application May 2, 1946, Serial No. 129,226

Term of patent 3½ years

(Cl. D89—1)

To all whom it may concern:

Be it known that we, Franklin J. Repp and Harry P. Yeager, citizens of the United States and residents of Milwaukee, in the county of Milwaukee and State of Wisconsin, and Louis B. Robbin and Louis B. Robbin, Jr., citizens of the United States and residents of Eagle, in the county of Waukesha and State of Wisconsin, have invented a new, original, and ornamental Design for a Coconut and Vegetable Grater, of which the following is a specification, reference being had to the accompanying drawing, forming part thereof.

Fig. 1 is a side elevational view of the coconut and vegetable grater, showing our new design.

Fig. 2 is a front elevational view of the same.

Fig. 3 is a top plan view of the coconut and vegetable grater.

Fig. 4 is a rear elevational view of the device, and

Fig. 5 is a bottom plan view of the device.

We claim:

The ornamental design for a coconut and vegetable grater, as shown.

FRANKLIN J. REPP.
